INVENTOR

John L. Meeks

UNITED STATES PATENT OFFICE.

JOHN L. MEEKS, OF BROOKLYN, NEW YORK.

ADJUSTABLE FOLDING SPRING BED-BOTTOM.

SPECIFICATION forming part of Letters Patent No. 352,480, dated November 9, 1886.

Application filed May 4, 1885. Serial No. 164,324. (No model.)

To all whom it may concern:

Be it known that I, JOHN L. MEEKS, a citizen of the United States, residing in the city of Brooklyn, in the county of Kings and State 5 of New York, have invented a new and useful Improvement in Adjustable Folding Spring Bed-Bottoms, of which the following is a specification.

My invention relates to that kind of spring 10 bed-bottoms in which volute or spiral springs are employed to produce the necessary elasticity, said springs being held in their positions by suitable means.

My invention has for its object to produce a 15 spring bed-bottom capable of adjustment in width, and that can be folded, rolled, or narrowed up, and thereby made to occupy less room for the purpose of shipping, storing, handling, or transportation. Suitable means 20 are provided to keep said bed-bottom at the required width when opened, and also to keep the same closed when rolled or narrowed up.

My invention will be set forth in the following description and claims.

25 In the accompanying drawings, Figure 1 represents a plan view of my improved adjustable folding spring bed-bottom; Fig. 2, a side view when open; Fig. 3, an end view showing the bed-bottom extended and attached to the bed-frame; Fig. 4, a view of the spring bed-bottom when closed; Fig. 5, an end view when rolled up. Fig. 6 is a modification showing the cross-strips formed of a number of coiled springs instead of a single coiled spring.

35 Similar letters refer to similar parts throughout the several views.

The bed-bottom consists of strips *a*, of wood or metal, extending lengthwise with a bedstead, and may rest on the bed-slats or be 40 otherwise connected to the bed-frame when in use. The strips *a* are connected together, as shown, by coil-springs *C*, fastened to strips *a*, and of one continuous coil of wire extending from side to side of the bed-bottom, or of a 45 number of coils fastened to and between the strips *a*. These coils are shown at *F*, Fig. 6, fastened to strips *a*, and are practically a continuous coiled-spring strip, such as *C*, extending from side to side of the bed-bottom. In 50 lieu of the coiled springs *C*, any equivalent elastic strip may be employed which serves

the same purpose—viz., which is both flexible and extensible. By means of these springs or flexible cross-connecting pieces or strips the bed-bottom can not only be adjusted laterally 55 to fit a bed-frame, but can also be rolled up in the smallest possible compass. Volute or spiral springs *C* are riveted or otherwise fastened to the strips *a*, and so arranged as to form no obstacle to the adjustment or folding up of the 60 bed-bottom.

The springs *C* are connected together by chains, springs, or cords in any suitable manner. To the top of the outer row of springs, *C*, on each side is secured a strip, *b*, to brace 65 the bed-bottom, having pivoted arms *d*, of metal or wood, which, when the bed-bottom is folded up, lie lengthwise with the strips *b*, so as to be out of the way, and when the bed-bottom is in use are turned out and engage the adjacent coil, thereby preventing the strips *b* from tilting.

The bed-bottom is held in place and secured to the adjusted width by arms *e*, pivoted to the outer strips, *a*, and having a slot by which 75 they are secured to a button or pin on the bed-frame. These arms *e* have also a double function in securing the bed-bottom when rolled by engaging buttons *f* on the other side strip, *a*, when brought into juxtaposition thereto. 80

It will thus be seen by the foregoing description that two desirable results are obtained in a single bed-bottom—viz., that it can be adjusted in width to fit the bed-frame and can also be compactly rolled up for transportation. 85

I am aware that bed-bottoms with flexible cross-strips which permit them to be rolled up are not new, and that bed-bottoms with springs to permit of lateral adjustment are not new; but I am not aware that bed-bottoms 90 combining by means of coiled springs both of these features are old.

Having thus described my invention, what I claim is as follows:

1. A bed-bottom composed of volute springs 95 and slats, connected together by coiled springs, so as to be adjusted laterally or rolled up, substantially as described.

2. A bed-bottom consisting of slats having volute springs, the slats being connected together by coiled springs, so that they can be 100 adjusted laterally or rolled up, and means,

substantially as described, whereby the bed-bottom is held in adjusted lateral position, substantially as described.

3. A folding bed-bottom composed of slats, 5 volute springs, and cross coil-springs connecting the slats together, and means for fastening the same when rolled up or adjusted to width, substantially as described.

4. The combination, with a laterally adjustable and folding bed-bottom having its slats 10 connected by coiled springs, of side strips with adjustable braces, substantially as described.

JOHN L. MEEKS.
